UNITED STATES PATENT OFFICE.

CHRISTOPHER B. RICE, JR., OF PIQUA, OHIO.

RAILWAY-SWITCH MECHANISM.

No. 923,580.

Specification of Letters Patent.

Patented June 1, 1909.

Application filed October 21, 1908. Serial No. 458,832.

To all whom it may concern:

Be it known that I, CHRISTOPHER B. RICE, Jr., of Piqua, in the county of Miami and State of Ohio, have invented certain new and 5 useful Improvements in Railway - Switch Mechanism; and I do hereby declare the following to be a full, clear, and exact description of the invention, such as will enable others skilled in the art to which it appertains to make and use the same.

My invention relates to improvements in railway switch operating mechanism, the object of the invention being to simplify and improve mechanism of the type illustrated 15 by Letters-Patent No. 765,195, granted to me on the 19th day of July 1904.

With this object in view, the invention consists in certain novel features of construction and combinations of parts as hereinafter 20 set forth and pointed out in the claims.

In the accompanying drawings; Figure 1 is a diagrammatic plan view illustrating my improvements; Figs. 2, 3 and 4 are views illustrating various details of construction.

25 1 represents the rails of a main track; 2 a siding, and 3 the pivoted switch rails. A bar 4 connects the switch rails and projects laterally from the track. With the free end of this bar, a rod 5 has a sliding connection, said rod passing freely through a projection 6 on the end of the bar, and provided with nuts or collars 7 at respective sides of said projection. The outer end of the rod 5 is pivotally attached to one arm of a bell-crank-lever 8, and the other arm of this lever is provided with rollers 9 disposed in a cam groove or way 10 in a wheel 11 located near the trackway.

40 The upper portion of the wheel 11 is provided with peripheral teeth to form a gear wheel 12, while the lower portion of the wheel is provided with a series of peripheral sockets 13 for a purpose hereinafter explained,—the intermediate peripheral portion of the wheel having a groove 14 for the accommodation of the short arm of the bell crank 8 to permit the rollers on the latter to operate in the cam groove 10.

45 The wheel 11 is mounted on a vertical shaft 15 rising from a suitable base 17, and on this base, a toothed segment 18 is pivotally mounted. This segment is adapted to mesh with the teeth of the gear wheel 12 and is provided with a flange 19 to overlap the 50 gear wheel and assist in insuring the proper meshing of the segment with the gear wheel.

To further insure the accurate engagement of the segment with the gear wheel, the latter is provided with lugs 20 to be engaged by the segment when the latter begins to engage 60 the teeth of the gear wheel.

The segment 18 is provided at its pivoted end with a laterally projecting arm 21, to the free end of which, one end of a rod 22 is connected. The other end of the rod 22 is connected with one arm of a bell-crank 23, and between its ends, said rod is provided with a turn-buckle 24 for adjusting its length and thus regulating the stroke of the segment 18.

The bell-crank 23 is located between the 70 rails of the track some distance in advance of the switch, and adjacent to said bell-crank, a wheel 25 is mounted between the rails. The wheel 25 is somewhat similar in construction to the wheel 11, being provided with a cam 75 groove or way 26 to receive rollers 27 on the end of the short arm of the bell-crank 23. The wheel 25 is provided with a worm wheel 28 located in a manner similar to the gear wheel 12 of the wheel 11 and receives motion 80 from a worm 29. The worm 29 is located centrally between the ends of a shaft 30 mounted in suitable bearings between the rails and disposed parallel with the latter. The shaft 30 is made with a groove 31, the 85 major portion of which is spirally arranged, but the ends of which are straight and parallel with the axis of the shaft.

The devices above described may be covered by a suitable plate or casing having a 90 slot therein for the passage of a shoe depending from a car, said shoe being adapted to pass through the groove 31 as the car moves over the trackway, and thus cause the rotation of the shaft 30. The rotary motion of 95 the shaft 30 is transmitted, through the medium of the worm 29 and worm wheel 28 to the wheel 25. As the wheel 25 is thus turned, motion will be transmitted, by means of the cam 26 to the bell-crank 23 and the latter 100 will, through the medium of the rod 22 and arm 21, operate the segment 18 to turn the wheel 11. Motion will be imparted by the wheel 11 (through the medium of the cam 10) to the bell crank 8, which latter effects the 105 throwing of the switch rails through the medium of the bar 4 and rod 5. By providing a sliding connection between the rod 5 and bar 4, the segment 18 can be brought completely into mesh with the gear teeth on wheel 11, before the motion of the latter will be transmitted to the switch rails.

Some distance behind the switch, track devices the same in construction as those above described, are located at 33 and connected by means of a system of rods and levers, with 5 another segment 34 to coöperate with the gear teeth of the wheel 11, so that the switch can be operated by a train after it has passed the switch, or by a train running in the opposite direction. Similarly, track devices 10 are located at 35 along the siding, so that a train running on the latter can operate the switch,—said track devices being connected by rods and levers with a segment 36 which coöperates with the gear teeth of the 15 wheel 11.

It is important to prevent the wheel 11 from moving too far when it is operated. For this purpose, I provide a locking bar 37 which is pivotally supported between its ends 20 in proximity to the wheel 11, and provided at its ends with teeth 38 to engage the notches 13 in the periphery of the wheel. On its rear edge, the locking bar is provided near its ends with cams 39 to be engaged by a roller 40 on 25 the segment 18. When said segment is moved in one direction or the other to transmit motion to the wheel 11, the roller 40 on said segment will coöperate with the cam 39 on one end of the locking bar and turn the 30 latter so as to cause one of the teeth 30 to engage one of the notches in the wheel 11 when the segment has moved the wheel 11 sufficiently to operate the switch, and thus lock said wheel against further movement. 35 It is apparent that the bar 37 will operate to lock the wheel 11 and prevent it from being thrown too far in either direction.

In order that the mechanism shall be operative manually, another segment 41 will be 40 provided to coöperate with the wheel 11, and this segment is connected by means of a rod 42 with an arm on a target shaft 43. A hand lever 44 is connected with the target shaft for operating the latter to actuate the 45 segment 41 and wheel 11 and throw the switch.

For the purpose of operating the target 45, when the switch is thrown, the devices now to be described may be employed. A bell-crank lever 46 has one of its arms connected 50 with the bell-crank 8 by means of a rod 47, and the other arm of the bell-crank 46 is connected, by means of a rod 48, with an arm 49 connected with the target shaft. The connecting rod 47 is made in two parts having 55 sliding connection with each other, so that the target will not be operated until the teeth of segment 18 shall have come fully and positively into mesh with the gear teeth 12 of wheel 11.

60 A target 50 may be located in advance of the switch and in proximity to the first-described track devices. The shaft of this target is provided with an arm 51, and this arm is connected by a rod 52, with the bell-crank 46, so that when the mechanism is op-

erated to throw the switch, both targets will also be operated.

Various slight changes in the details of construction of my invention, might be made without departing from the spirit thereof or 70 limiting its scope and hence I do not wish to restrict myself to the exact details herein set forth.

Having fully described my invention, what I claim as new and desire to secure by Letters-Patent, is:—

1. In a railway switch mechanism, the combination with a switch rail and a wheel located a distance therefrom and provided with a worm gear, of a shaft located parallel 80 with the track rails and having a worm to mesh with said worm gear, said shaft having a spiral way to receive a shoe on a car for rotating said shaft, and mechanism between said wheel and switch rail for throwing the 85 latter, when said shaft and wheel are turned.

2. In a railway switch, the combination with a switch rail, of a wheel located a distance from the switch rail and provided with a worm gear and a cam, of a shaft located parallel with the track rails and provided with a worm to mesh with said worm gear, said shaft having a spiral groove to receive a shoe carried by a car, a bell-crank having one of its arms coöoperating with the 90 cam in said wheel, and mechanism interposed between the other arm of said bell-crank and the switch rail for throwing the 95 latter.

3. In a railway switch mechanism, the 100 combination with a switch rail, of a wheel located in proximity thereto and provided with a cam and with gear teeth, a bell-crank having one arm coöperating with said cam, a sliding lost-motion connection between the 105 other arm of said bell-crank and the switch rail, a segment to coöperate with said gear teeth, a track instrument, and connections between said track instrument and said segment.

4. In a railway switch mechanism, the combination with a switch rail, of a wheel located in proximity thereto and provided with a cam, connections between said cam and switch rail, means for turning said wheel to operate the switch rail, and means for locking said wheel when the switch rail shall have been thrown.

5. In a railway switch mechanism, the combination with a switch rail, of a wheel located in proximity thereto, said wheel having a cam, connections between said cam and switch rail, a segment to actuate said wheel, and means controlled by said segment to lock said wheel when the switch rail shall have been thrown.

6. In a railway switch mechanism, the combination with a switch rail, of a wheel located in proximity thereto and provided with gear teeth, said wheel also having a 130

cam, connections between said cam and the switch rail, a toothed segment to mesh with said gear teeth, a locking bar to engage said wheel and lock the same when the switch 5 has been thrown, means on the segment to operate said locking bar, and means for operating the segment.

7. In a railway switch mechanism, the combination with a switch rail, of a wheel 10 located in proximity thereto, means intermediate of said wheel and switch rail for throwing the latter, means for locking said wheel when the switch rail has been thrown and means for operating said wheel.

15 8. In a railway switch mechanism, the combination with a switch rail, of a wheel located in proximity thereto, means co-operating with said wheel and switch rail for operating the latter, a gear wheel movable with said first-mentioned wheel, a toothed segment to mesh with said gear wheel, a locking bar to engage said wheel, cams on said locking bar, a projection on the segment to co-operate with said cams to control 20 the operation of said locking bar, and means for operating said segment.

9. In a railway switch mechanism, the combination with a switch rail, of a wheel located in proximity thereto and provided 25 with a cam, a bell-crank co-operating with said cam and with the switch rail, a target, connections between said target and bell-crank, and means for turning said wheel.

10. In a railway switch mechanism, the combination with a switch rail, of a wheel 30

located in proximity thereto and provided with a cam, a bell-crank co-operating with said bell-crank and switch rail, a track instrument, connections between said track instrument and wheel for operating the latter, a target near the switch rail, a target 40 near the track instrument, and devices connected with said bell-crank for operating both of said targets when the switch rail is thrown. 45

11. In a railway switch mechanism, the combination with a switch rail, of a wheel located in proximity thereto, said wheel having a cam, a bell-crank co-operating with said cam and with the switch rail, gear 50 teeth on said wheel, a toothed segment to mesh with said gear teeth, lugs on the wheel to be engaged by said segment, an arm projecting from said segment, a wheel located a distance from the switch rail and provided 55 with a cam, means operative from a car to actuated said last-mentioned wheel, a bell-crank having one of its arms co-operating with the cam of said last-mentioned wheel, and an adjustable rod connecting the other 60 arm of said last-mentioned bell-crank with the arm on the segment.

In testimony whereof, I have signed this specification in the presence of two subscribing witnesses.
